UNITED STATES PATENT OFFICE.

ALBERT VORHEES CULVER, OF FRANKFORT, INDIANA.

FURNACE.

Application filed August 3, 1925. Serial No. 47,894.

My said invention relates to a furnace here illustrated as being of the "pipeless" type and it is an object of the same to improve the heating action of the furnace and the circulation of air while decreasing the amount of fuel required. My invention is, however, not limited to furnaces of any especial variety, but extends to furnaces and heat-generating plants in general.

10 Referring to the accompanying drawings, which are made a part hereof and on which similar reference characters indicate similar parts,

Figure 1 is a front elevation of my device with parts broken away, and

15 Figure 2, a section on line 2—2 of Figure 1.

In the drawings reference character 10 indicates the outer jacket or casing of the 20 furnace here shown as extending from the floor A up to the floor 11 of the building in which the furnace is used. An inner jacket 12 is mounted within the casing 10 and extends from the floor 11 to a point adjacent 25 the floor A and surrounds the furnace proper or other fire container 13 which is provided with an ash pit door 14, a fire door 15 and an outlet 15' for smoke.

The principal feature of the invention 30 consists in omitting all drafts and draft openings from the doors and from the front of the furnace. To provide the necessary draft I have arranged dampers 16 in the door frame or extensions 17 of the furnace wall at 35 opposite sides of the door space. It will be readily seen that when these dampers are opened air will be admitted to the space beneath the grate in sufficient quantity to maintain combustion. This air is taken from 40 the circulation through the building coming down through the space between the inner and outer jackets and diminishing, to the slight extent indicated, the amount of air passing up between the inner jacket and the 45 furnace proper.

A pair of pipes 18 are provided at opposite sides of the door space between the furnace proper and the inner jacket 12 which pipes are adapted to receive air at their 50 lower ends in similar manner to the openings just described and at their upper ends admit it to the space above the grate in well-known manner so as to keep the fire from going out when the dampers 16 are 55 closed. Dampers 19 are provided in the

pipes 18 and these dampers have a crank handle 20 at the outside of the furnace by means of which the dampers 19 may be opened to various degrees or closed at will for opening and closing the passages 60 through the pipes 18. A cord or cable 22 leads upward from the righthand draft 16 to a point in the room above or adjacent thereto, and a similar cable leads from the other draft 16 over a pair of pulleys 23, 24 65 to the first-named cable so that both lower drafts can be operated without entering the furnace room. In similar manner the dampers 16 have a handle at 21 whereby they may be operated. It will be seen that the draft 70 to the space above the grate may be opened or closed independently of the draft to the space below the grate thus providing for all the usual draft variations by which the 75 fire is controlled.

Instead of drawing the air for the firebox from the outside or from the basement or other chamber in which the furnace is located it is drawn from the lower heated 80 part of the building heated by the furnace and so improves the circulation in the building. The air in the building being pre-heated does not require so much heating as the cold air ordinarily used and thus reduces 85 the amount of fuel required for maintaining the desired temperature in the building.

It will be obvious to those skilled in the art that various changes may be made in my device without departing from the spirit of the invention and therefore I do not limit myself to what is shown in the drawings and described in the specification but only as indicated in the appended claims. It will also be obvious how my invention can be applied 90 to furnaces and heat-generating plants of other types than the pipeless furnace here depicted.

Having thus fully described my said invention what I claim as new and desire to 95 secure by Letters Patent is:

1. The combination in a pipeless furnace of a fire box, inner and outer casings for the fire box terminating in the door frame said door frame having openings in its sides near the bottom below the level of the grates for admitting air directly below the grates, closures for said openings said door frame also having openings in its sides near the top above the level of the grates for admitting air directly above the grates, and 105 110

means for graduating the flow of air through said last-mentioned openings, substantially as set forth.

2. The combination in a pipeless furnace of a fire box, inner and outer casings for the fire box terminating in the door frame said door frame having openings in its sides near the bottom below the level of the grates for admitting air directly below the grates, 5 closures for said openings said door frame also having openings in its sides near the top above the level of the grates for admitting air directly above the grates, pipes having their upper ends secured about the last-mentioned openings and terminating at substantially the same level as the first-mentioned openings, and means for graduating the flow of air through said pipes, substantially as set forth.
- 10 3. The combination in a pipeless furnace, of a fire box, inner and outer casings for the

fire box terminating in the door frame said door frame having openings in its sides near the bottom below the level of the grates for admitting air directly below the grates, 25 closures for said openings said door frame also having openings in its sides near the top above the level of the grates for admitting air directly above the grates, pipes having their upper ends secured about the last-mentioned openings and terminating at substantially the same level as the first-mentioned openings in the path of the closures for said first-mentioned openings whereby said closures may be operated to 30 cut off the air supply to either the upper or the lower openings, substantially as set forth.

In witness whereof, I have hereunto set my hand and seal at Frankfort, Indiana, this 24th day of July, A. D. nineteen hundred and twenty-five.

ALBERT VORHEES CULVER, [L.S.]
